BOW NECKTIE

Samuel Semmel, New York, N. Y.

Application February 29, 1944, Serial No. 524,361

2 Claims. (Cl. 2—155)

1

This invention relates to bow neckties, as worn in connection with shirt collars, which neckties are manufactured of assembled different parts to resemble a bow made of a single length and tied by the wearer.

The principal object of the invention is to provide a simplified and conveniently and economically manufacturable, conveniently wearable, strong, durable, improved, low cost and well appearing necktie of the above type.

Another object is to provide a necktie, the wings of which have pointed ends with provisions for converting the necktie into one having a straight-edged appearance.

A further object is to provide a necktie, the neck-band of which is furnished with improved means for varying the overall length or size thereof.

A still further object is to provide a necktie, the neck-band of which is furnished with improved means for maintaining the attaching eye thereof against operative dislocation.

A still further object is to provide improvements in a necktie of the above type which will render it made of differently patterned fabrics.

An additional object of the invention is to provide a simplified and conveniently and economically manufacturable, conveniently wearable, strong, durable, improved, low cost and well appearing necktie embodying provisions for its reversibility in the wearing thereof.

Other objects and advantages will hereinafter appear.

In the accompanying drawings,

Fig. 1 is an elevational view of a tube, forming a part of the bow necktie, showing it as it appears during its manufacture.

Fig. 2 is an end view of the tube shown in Fig. 1.

Fig. 3 is an elevational view of a reversed form of the tube shown in Fig. 1.

Fig. 4 is an end view of the tube as it appears in the form shown in Fig. 3.

Fig. 5 illustrates a lining used in connection with the tube shown in Fig. 3.

Fig. 6 is an elevation of the bow necktie constituting the invention, showing it as it appears at the rear thereof, without its knot tied therewith.

Fig. 7 is a top plan view of the necktie shown in Fig. 6.

Fig. 8 is a view similar to Fig. 7, but showing a modification of the invention.

Fig. 9 is a view similar to Fig. 7, in a reduced scale showing another modification of the invention.

2

Fig. 10 is an elevational view, showing an end view of the bow necktie of Fig. 6, and of the neck-band utilized in connection with this necktie.

Fig. 11 is a plan view of the neck-band shown in Fig. 10.

Figs. 12, 13, 14 illustrate details used in connection with the neckband shown in Fig. 11.

Fig. 15 is an elevational view of a tube, showing a modification of the one illustrated in Fig. 1.

10. Fig. 16 is an end view of the tube shown in Fig. 15.

Fig. 17 is a side elevation of the tube shown in Fig. 16, with the end portion thereof in folded condition.

15. Figs. 18, 19, 20, 21 are views correspondingly similar to Figs. 1, 2, 3, 4, and showing another modification of the invention.

Fig. 22 is a rear elevational view of a bow necktie, showing the improvements as applied to a 20 reversible type tie.

Fig. 23 is a top plan view of the necktie shown in Fig. 22.

Fig. 24 is a view similar to Fig. 23, but showing the tie in reversed condition.

25. Figs. 25 and 26 show a further modification of the invention.

Fig. 27 is an elevational view of a tubular member, as it appears before assemblage of the modification shown in Fig. 9.

30. In the manufacture of the necktie 1, Fig. 6, there is first prepared a pair of tubular members 2, Figs. 1, 2, consisting of a fabric sheet 3, bent upon itself at 4 and having its lateral edges 5 secured by a stitching 6. The edges 7 of the end of tube 2 are similarly secured by a stitching 8, and the corner portion 2a is cut off, leaving an opening 9 for entry into the tube. The tube 2 is then reversed and collapsed so as to position its stitching 6 to the rear and along the middle portion of the tube, as shown in Fig. 4. The end portion of the tube at region 9 is then inserted 35 backwardly thereinto, in such manner, Fig. 3, that its opposite region is formed into a pointed portion 10 with a pocket 11 adjacent thereto and the opening 9 located in the bottom of the pocket, 40 the provision of said opening and the cutting away of part 2a being to permit insertion of a stick therethrough to aid in inserting and shaping of the pocket and to eliminate a tuft which 45 would be thereat produced by the part 2a, which tuft would bulge and disfigure the tube. A lining 50 12, Fig. 5, is then inserted into the tube 2, with its end portion 12a therein positioned behind the pocket 11 and between walls comprising the end portion 10, and the lining portion 12a has thereto

55

secured a layer 13 having therein flexible metallic wires 14. The layer 13 and wires 14 serve to maintain the portion 10 in requisite projected position, and permit neat and efficient folding of said portion along a line 15 and the insertion of the portion into the pocket 11, thereby converting the tube 2 from one having a pointed end 10 to that of straight-edged tube, as will be herein-after further seen.

Both tubular members 2, as thus completed, are then folded and positioned against each other in the manner illustrated in Figs. 6, 7, and the edge of each is secured by a stitching 16 to a neck-band 17, Fig. 10, whereupon said band may be tied around the combined members 2 into a knot 18, Fig. 6, thereby completing the simulated bow necktie, comprising the said knot, with tie-wings 2b, 2c, 2d, 2e. As the necktie 1 is thus completed it may be worn either in a pointed wing form, with the portions 10 extended, or it may be converted into a straight-edged tie by folding the portions 10 about line 15 and inserting them into the pockets 11, as indicated.

In the modification shown in Fig. 8, the necktie 1 is converted into a straight-edged form by providing the rears of its pointed portions 10 with clasps 18' which interlock with cooperating clasp members 19 secured to the rear of the tie body.

In the modification shown in Fig. 9, the necktie is made up of a single tubular member 20, Fig. 27, which is folded in the manner illustrated in Fig. 9 to provide the tie-wings 2b, 2c, 2d, 2e, the completed tube 20 being in all other respects similar to the finished member 2 shown in Fig. 3.

The neck-band 17, Figs. 10, 11, comprises two parts 17a, 17b, the former terminating in an eye 21 and being secured as shown to a fitting 22, while part 17b threads through the fitting 22 as illustrated, and its terminals carry hooks 23, 24. The band part 17a is tubular and its wall 17c is provided with a series of holes 25, with any one of which the hook 23 of band part 17b is adapted to engage and interlock, by which means the neckband 17 may be adjusted and secured to any selected overall length and size desired, and its hook 24 and eye 21 may be resorted to for securing the necktie to the wearer's collar. In the modification shown in Fig. 14, the hook 23 is provided with a sharp point 23a to permit it to penetrate and engage the face 17c at points between the holes 25, in case finer adjustments are desired for the overall length of neck-band 17.

As shown in Figs. 12, 13, the eye 21 is hinged at 26 to a plate 27 which is held in a loop 28 of the terminal of band-part 17a, by which means the eye 21 is maintained against dislocation and in proper operative position upon the neck-band.

In the modification shown in Figs. 15-17, a tubular member 29, corresponding to the tube 2 in Fig. 3, is made of two fabric sheets 30 and secured by a stitching 31 around its periphery, with the lining 12 enclosed therewithin, and its pointed end portion 29a is converted into appearance of a straight-edged tie-wing by folding it backwardly about a line 32, as seen in Fig. 17.

According to the modification shown in Figs. 18-21, a tubular member 33, corresponding to the tube 2 in Fig. 1, is made of two fabric sheets 34, 35 of different types of patterns, and are secured to each other by stitchings 36, 37 at both of their lateral edges. The tube 33 is then re-

versed and collapsed to position said stitchings along the middle portions of the tube, whereby when the necktie made from two of these tubes is completed it presents an appearance as made from two differently patterned fabrics, as illustrated in Fig. 20.

According to the modification shown in Figs. 22-24, the improvements of the invention are shown as embodied in connection with a reversible type bow necktie, comprising a long tubular member 38 to the face 39 of which is secured a tie-wing member 40 provided with pointed end portions 40a, and both of said members are secured by stitching to a neck-band 17, as hereinabove described in connection with Fig. 10. The terminals of tube 38 carry cooperating clasping devices 41, 42, so that when the free portions 38a of the tube are brought together rearwardly and clasped to each other, as shown in Figs. 22, 23, and the neck-band 17 is tied into a knot 43 the necktie is completed, with the portions 40a extended, simulating the appearance of a pointed wing bow tie. When it is desired to convert this necktie into appearance of a straight-edged one, each end portion 40a is bent about a line 44 inserted between the members 38, 39, as indicated.

When it is desired to wear this necktie in a reversed condition, the free tube-portions 38a thereof are swung back oppositely and forwardly to a position against the face 40b of member 40, Fig. 24, and are clasped to each other, thereby presenting the face 38b of member 38 as the front of the necktie.

In the modification shown in Figs. 25, 26, a tubular member 44 is made from a single elongated fabric sheet 45, by folding its corner portions 46 thereagainst and securing them to each other by a stitching 47, and then folding its lateral areas 48 thereagainst along lines 49a and securing them by a stitching 49, resulting in a tube having a pointed end portion 50. When this tube is made into a tie to constitute the wing, its pointed end 50 may be converted to a straight-edged form by folding it rearwardly along a line 50a, in above described manner.

Variations may be resorted to within the scope of the invention, and portions of the improvements may be used without others.

Having thus described my invention, I claim:

1. A band for a necktie having the combination of a first part, a second part, a framing, a median portion of said first part being adapted to carry the necktie and the first part threading through said framing, a terminal of said second part being secured to said framing and the second part having therewith a series of attaching means, a terminal of said first part carrying a device for selectively engaging any one of said means for adjusting the overall length of the band, and the opposing terminals of both of said first and second parts carrying devices for detachably engaging them to each other for tying the band to the wearer's collar.

2. A band for a necktie having the combination of a first part, a second part, a framing, a median portion of said first part being adapted to carry the necktie and the first part threading through said framing, a terminal of said second part being secured to said framing, a terminal of said first part carrying a hook adapted to pierce said second part at any point therewith for adjusting the overall length of the band, and the opposing terminals of said first and second parts carrying devices

for detachably engaging them to each other for
tying the band to the wearer's collar.

SAMUEL SEMMEL.
